DESIGN FOR AN ALL METAL CHAIR

Anthony B. King, Brooklyn, and Charles L.
Martino, Bronx, N. Y.

Application September 25, 1945, Serial No. 122,322

Term of patent 14 years

(Cl. D15—1)

To all whom it may concern:

Be it known that Charles L. Martino and Anthony B. King, citizens of the United States of America, residing at Bronx, in the county of Bronx and State of New York, and at Brooklyn, in the county of Kings and State of New York, respectively, have invented a new, original, and ornamental Design for an All Metal Chair, of which the following is a specification, reference being had to the accompanying drawing, forming part thereof.

In the drawing

Figure 1 is a side elevational view of an all metal chair showing our new design.

Fig. 2 is a front elevational view thereof.

Fig. 3 is a rear elevational view thereof.

Fig. 4 is a bottom plan view.

In the drawing the intersecting lines represent cushion members formed entirely from metal wire screen material.

We claim:

The ornamental design for an all metal chair, as shown and described.

ANTHONY B. KING.
CHARLES L. MARTINO.
